POLAR RELAY

Robert J. Little, Gates, and Thomas J. Judge,
Rochester, N. Y., assignors to General Railway
Signal Company, Rochester, N. Y.

Application September 13, 1941, Serial No. 410,724

9 Claims. (Cl. 175—320)

This invention relates in general to relays for use in railway signalling systems, and the like, and has more particular reference to an improved slow release quick pick-up retained neutral polar type of relay.

In certain situations, as will appear more clear from the following, it is desirable in the case of neutral polar relays, to provide a device which is quick to pick up upon being energized, but which is slow to release when deenergized, and which retains its neutral armature in picked up position while energization of the relay is being pole changed and during any short deenergization. This is particularly the case with a relay employed to respond to current which is so coded as to comprise a series of short current impulses separated by short blank, or off current periods, and in which the current impulses are of one polarity for some, and of the other polarity during another period of time, and in which the rate of coding may be relatively fast or slow.

In cases as referred to just above, a relay which is slow to release so as to bridge over the blank periods of code, may not be quick enough to pick up to respond to the short spaced current impulses. Furthermore, if the relay be quick enough in picking up to respond to the current impulses, it may not be slow releasing enough to enable it to hold up over the off periods of code. Thus, it is desirable to provide a relay which is quick to respond to energy and to reach its picked up position, which is slow to release and hence retains its picked up condition during the off periods of code, and which is provided with suitable retaining means so that it can retain its neutral armature in picked up position during pole changing of its energization.

With the above and other objects in view, it is proposed in accordance with the present invention to provide a relay having a main winding and a retaining winding and so associate these windings with slow release means and a rectifier as to accomplish the above purposes, and to accomplish all this in an economical and efficient manner.

Further objects, purposes and characteristic features of the present invention will appear as the description progresses, reference being made to the accompanying drawings, showing solely by way of example and in no manner whatsoever in a limiting sense, one form which the invention can assume. In the drawings:

Fig. 1 is a sectional elevation of a commercialized form of relay embodying one form of this invention.

Fig. 2 is a schematic view of a relay embodying the present invention.

Fig. 3 is a schematic view of a track signalling system in which a relay, constructed in accordance with this invention, is of particular value.

Referring now to the drawings and first to Fig. 1, there is here shown a relay having a usual top plate 1, and an enclosing casing 2 connected to the plate as by bolt means 3. This relay, in general, is constructed as disclosed in the O. S. Field Patent 1,749,331, granted March 4, 1930, and in the J. E. Willing Patent 1,969,055, granted August 7, 1934. Thus, a detailed description of the construction other than that which is particularly applicable to the present invention should be quite unnecessary.

The construction of the relay and the circuit arrangement can be easily understood from a consideration of Fig. 2, in which figure the parts corresponding to those of Fig. 1, bear like reference characters.

In Fig. 2 is shown a pair of main cores MC interconnected by a back strap 4, and a pair of retaining cores RC interconnected by a back strap 5. On the main cores are main windings MW, and on one of the retaining cores is a retaining winding RW. The other retaining core is supplied with choke means in the form of an elongated copper cylinder S, sleeved on the core, and furnishing a low resistance short-circuited winding on this core. In some cases copper sleeve may be omitted by using full winding. The retaining winding is connected by wires 6 and 7 to the output side of a full-wave rectifier Rec., the input side of the rectifier being connected by means of wires 8 and 9 across the major portion of the main winding MW. A few turns of the main winding, at each end of the same, such as 10 and 11, are positioned ahead of the wires 8 and 9 so as to supply an inductive winding or choke at each side of the rectifier for protection against lightning, and the like.

The main winding is shown as connected to a source of energy such as a battery 12 through a pole changing switch 13—14 controlled by any usual means as a hand lever 15, whereby the lever can be operated to either deenergize the relay or to energize it with one, or the other, polarity of current.

A movable neutral armature NA is shown as pivoted at 16 and positioned to be attracted to the pole shoes 17 and 18 of the main cores and to the pole shoes 19 and 20 of the retaining cores, when the respective windings are energized. This neutral armature carries a contact finger 21 mov-

able by gravity to make up a back point 22, and movable to make up a front point 23 under energized conditions.

A polar armature PA is provided on a pivot 24 and carries a contact finger 25 which is electrically controlled by the main cores and windings to assume either a normal or reverse energized position against a normal contact point 26 or a reverse contact point 27, and to retain its energized position until energized to a different position.

The relay constructed as described above thus has both a neutral and a polar armature, and upon energization with either polarity of current the neutral armature is picked up, and the polar armature, dependent upon polarity of energization, moves to either its normal or reverse position. Upon deenergization of the relay, the decay of flux in the main cores induces a voltage in the main windings and likewise the decay of flux in the retaining cores induces a voltage in the retaining winding, which voltages are in the same direction in a series circuit including these windings, and the rectifier Rec. This circuit can be traced to include wire 8, rectifier Rec., wire 6, winding RW, wire 7, rectifier Rec., wire 9, the major portion of the main winding MW, and wire 8. This circuit allows a considerable current to flow and thus opposes the decay of flux in both the main windings and the retaining winding. Furthermore, the decay of flux in the retaining cores induces a voltage in sleeve S to cause a current to flow therein which strongly opposes the decay of flux in these cores. All this results in producing a very slow releasing operation of the relay.

Regardless of slow release means, such as described above, if the polarity of energization is changed, the flux in the cores must pass through zero, and hence the neutral armature will release unless means is provided to prevent this. By employing the rectifier Rec., it can be seen that the direction of current flow in the retaining winding is always in the same direction regardless of the direction of its energization from the source 12. Accordingly, the relay will effectually hold up during the blank or "off" periods of current occurring in a code and its neutral armature will be retained in attracted position when the code is changed from a plurality of current impulses of one polarity to a plurality of current impulses of the other polarity. Since the slow release means in the form of the sleeve S is placed on the core structure of the retaining means it will not adversely affect the operation of the main windings in rapidly picking up the armatures. Thus, with this arrangement of parts the slow release effect is produced not only by the rectifier and by the sleeve S but by the connection between the main winding and the retaining winding in a series circuit with each other.

Referring now to Fig. 3, there is here shown a fragmentary portion of a railway wayside signal system of the absolute-permissive-block type, such, for example, as disclosed in the Judge application, Ser. No. 378,961, filed February 14, 1941, for "Coded track circuit signalling systems." For the purpose of disclosing the present invention, it should be necessary to merely summarize the operation of this system whereby to point out the advantages accruing from the employment in such systems of relays constructed in accordance with the present invention.

A stretch of single track constituted by track rails 30 is shown, signalled for east bound and

west bound travel, by means of signals S12, S14, S18, and signals S19, S17 and S13, respectively.

In systems of this type, at one end of each block, such as the block having the entering signals S14 and S17, there is a code transmitter CT which operates to intermittently place energy across the track rails at one end of the block at a desired rate, as for example, 75 times per minute. At the other end of the block a track relay

- 10 TR responds to the code and follows it so as to pick up and release for each "on" and "off" period of current. This track relay, through its front point, controls a front repeater relay FP while through its back point and in conjunction 15 with the relay FP, controls a front-back repeater FBP. Thus, upon the coder failing to function to intermittently energize the track circuit and also upon occupancy, the front-back repeater relay releases to indicate occupancy and control 20 the signals.

The code transmitter and the track relay operate in synchronism whereby when both relays are in attracted position, the signal control relay 14HD is energized while when both are in retracted position the signal control relay 17HD is energized.

- These HD relays can, to advantage, be constructed in accordance with the present invention, and as described above. Hence, with a 75 30 rate code in force, they are energized intermittently 75 times per minute, and are deenergized the same number of times per minute. Accordingly, a slow release relay, which is not fast to pick up might easily fail to pick up in 35 response to the "on" periods of code, while on the other hand, a fast pick-up relay, which is not slow to release, might fail to hold up during the "off" periods of code. The retaining winding on the retaining core can be adjusted 40 in any desirable way to make the relay as slow releasing as desired without interfering with the quick pick-up characteristics of the relay and furthermore, the inductive effect of the main winding on the rectifier fed retaining coil makes 45 the relay additionally slow to release.

The slow release means, shown in the form of the sleeve S, is but one embodiment of the invention and this sleeve can be replaced by a longer or a shorter one, or by a winding of heavy wire with suitable adjustment taps.

- The signals such as S14, employed in this system are of the SA type, as for example, those described in the Judge application Ser. No. 378,961, referred to above. This type of signal 55 ordinarily requires a home distant or HD relay, to control it, and requires a separate yellow-green repeater relay to repeat the yellow and the green indications of the signal and retain its picked up position during the movement of the signal contacts from one polar position to the other. This yellow-green repeater prevents improper and undesired operation of the signals to the rear upon a change from yellow to green, for example, of a signal ahead.

With HD relays constructed as described above, and as diagrammatically illustrated in connection with relay 14HD, for example, no repeater relay is required in connection with the type SA signal. This is because this type of relay 65 retains its neutral contacts closed not only while the relay is deenergized between current impulses but while the energization of the relay is pole changed, and at the same time is quick to pick up.

70 Let us assume that signal S14 is displaying

a caution indication and that signal S18 which is next in advance thereof, is displaying a stop indication due to occupancy of the track section at the entrance to which signal S18 is placed. The signal next to the rear of signal S14, that is, signal S12, will of course be displaying a proceed indication. Assume now that the train advances so as to cause signal S18 to change from stop to caution and that signal S14 changes from caution to clear. Signal S12, already at clear, should not change, but when the control relay 14HD for signal S14 swings its polar contacts from one side to the other to change the signal from caution to clear, if the neutral armature should release even momentarily, the polarity of energization on the control relay for signal S12 would momentarily change, and its green clear indication would change to yellow, or caution, and then back to green. This change in the control relay for signal S12 would cause a momentary change in the signal from green to yellow and back again of the signal next in the rear of it, and likewise throughout the entire stretch of track.

The operation of the system shown in Fig. 3 should be clear from the drawing without more detailed explanation than that given above, although it might be mentioned that the usual directional stick relays are employed for the tumble-down circuits, such as the stick relays having the contacts 13S, 14S, etc. Thus, if an east bound train enters the stretch of track all of the west bound signals such as S13, S17, etc., will go to stop, since the controlling stick relays, such as 13S, etc., will not have picked up with this direction of traffic. The stick relays for the other direction, that is, 14S, 18S, etc., will have picked up, however. It further might be noted that the energy for picking up relay 14HD is indicated by (+) and (-) at the right-hand side of the figure of drawing while that for relay 17HD is at the left-hand side of the drawing.

From the above disclosure it can be realized that a retained neutral polar relay is provided which is simple in construction and dependable in operation, and which can be made as slow to release as is desired without interfering with its quick pick-up characteristic, and which retains its neutral armature in energized position not only during short "off" periods of current, but also when the polarity of energization of the relay is changed.

The above rather specific description of one form of the present invention is given solely by way of example and is not intended in any manner whatsoever in a limiting sense. It is to be understood that various modifications, adaptations and alterations may be applied to meet the requirements of practice without in any manner departing from the spirit or scope of the invention, except as limited by the scope of the appended claims.

Having described our invention, we now claim:

1. In a polar retained neutral relay, in combination, a main core, a retaining core spaced from the main core, a main winding on the main core, a retaining winding on the retaining core, a movable polarized armature magnetically associated with the main core, a movable neutral armature associated with both the main core and the retaining core, a full wave rectifier, circuit means conductively connecting the input side of the rectifier across the main winding and the output side of the rectifier across the retaining

winding, and means for connecting electrical energy of either polarity across the main winding for energizing the said two windings in multiple.

2. In a polar retained neutral relay, in combination, a main core, a retaining core spaced from the main core, a main winding on the main core, a retaining winding on the retaining core, a movable polarized armature magnetically associated with the main core, a movable neutral armature associated with both the main core and the retaining core, a full wave rectifier, circuit means conductively connecting the input side of the rectifier across the main winding and the output side of the rectifier across the retaining winding, means for connecting electrical energy of either polarity across the main winding, and means associated with the retaining core for opposing flux changes in the retaining core.

3. In a polar retained neutral relay, in combination, a main core, a retaining core spaced from the main core, a main winding on the main core, a retaining winding on the retaining core, a movable polarized armature magnetically associated with the main core, a movable neutral armature associated with both the main core and the retaining core, a full wave rectifier, circuit means conductively connecting the input side of the rectifier across the main winding and the output side of the rectifier across the retaining winding, means for connecting electrical energy of either polarity across the main winding, and a low resistance winding on the retaining core for opposing flux changes in this core.

4. In a polar retained neutral relay, in combination, a main core, a retaining core spaced from the main core, a main winding on the main core, a retaining winding on the retaining core, a movable polarized armature magnetically associated with the main core, a movable neutral armature associated with both the main core and the retaining core, a full wave rectifier, circuit means conductively connecting the input side of the rectifier across the main winding and the output side of the rectifier across the retaining winding, means for connecting electrical energy of either polarity across the main winding, and a copper sleeve on the retaining core for opposing flux changes in the core whereby current induced in the main winding can flow in series, through the main and retaining winding.

5. In a polar retained neutral relay, in combination, a main core, a retaining core spaced from the main core, a main winding on the main core, a retaining winding on the retaining core, a movable polarized armature magnetically associated with the main core, a movable neutral armature associated with both the main core and the retaining core, circuit means conductively connecting the two windings in series, means for connecting energy of either polarity across the main winding, and means in said circuit means for maintaining flow of current through the retaining winding always in the same direction, regardless of the polarity of the energy applied to the main winding.

6. In a polar retained neutral relay, in combination, a main core, a retaining core spaced from the main core, a main winding on the main core, a retaining winding on the retaining core, a movable polarized armature magnetically associated with the main core, a movable neutral armature associated with both the main core and the retaining core, circuit means conductively connecting the two windings in series, means for connecting the two windings, in multiple, across

energy of either polarity, and asymmetric means in said circuit means for maintaining flow of current through the retaining winding in the same direction, regardless of the polarity of the energy applied.

7. In combination with a two wire polarized line circuit, a polar retained neutral relay including a main core, a retaining core spaced from the main core, a main winding on the main core, a retaining winding on the retaining core, a movable polarized armature magnetically associated with the main core, a movable neutral armature associated with both the main core and the retaining core, a full wave rectifier, circuit means conductively connecting the input side of the rectifier across the main winding and the output side of the rectifier across the retaining winding, and means for connecting the line circuit across the main winding.

8. In combination with a two wire polarized line circuit, a polar retained neutral relay including a main core, a retaining core spaced from the main core, a main winding on the main core, a retaining winding on the retaining core, a movable polarized armature magnetically associated

with the main core, a movable neutral armature associated with both the main core and the retaining core, a full wave rectifier, circuit means conductively connecting the input side of the rectifier across the main winding and the output side of the rectifier across the retaining winding, means for connecting the line circuit across the main winding, and means associated with the retaining core for opposing flux changes in the retaining core.

9. In a retained neutral relay, in combination, a main core, a retaining core spaced from the main core, a main winding on the main core, a retaining winding on the retaining core, a movable neutral armature associated with both the main core and the retaining core, a full wave rectifier, circuit means conductively connecting the input side of the rectifier across the main winding and the output side of the rectifier across the retaining winding, and means for connecting the line circuit across the main winding for energizing the said two windings in multiple.
